PIPETTE AND METHOD OF MAKING SAME

Robert L. Elliot, Winchester, Mass., and Edward M. Lavor, Norfolk, Va.

Application February 19, 1943, Serial No. 476,460

1 Claim. (Cl. 23—292)

Our present invention relates to clinical and other pipettes and like glass devices, and to their manufacture. More particularly it aims to provide an improved process for installing mixing elements or beads in the mixing chambers of devices of this class, and correspondingly to improve the resultant structures, as well as to simplify and improve the pipettes in other respects.

In the drawing illustrating by way of example one embodiment of the invention, and representing the several steps of the novel manufacturing process:

Fig. 1 is an elevation of a mixing or diluting pipette in accordance with the invention;

Figs. 2 to 5 inclusive are a series of enlarged cross-sections of the mixing chamber of the pipette such as that of Fig. 1, showing several succeeding stages in the insertion of the mixing element;

Fig. 6 is an elevational enlargement of a portion of Fig. 1; and

Fig. 7 is a partially diagrammatic view explanatory of prior practice.

Pipettes such as here concerned are employed for diluting in accurate proportions small quantities of liquids. One of their main fields of use is in diluting blood specimens in preparation for obtaining counts of the red or the white corpuscles. For such purpose a determined quantity of the blood is diluted in an appropriate liquid agent to destroy one or the other type of the corpuscles, the white ones where a count of the red corpuscles is to be made, or the red ones if the white corpuscles are to be counted.

Referring now to Fig. 1, such pipette in general comprises a rod-like glass body or stem 1 having centrally throughout its length a capillary tubular channel 2 opening at the outer and usually pointed end 3. At the other or inner end of the stem the capillary channel 2 communicates with a mixing chamber 4. Beyond the latter is a relatively short section or neck 5 of the glass tubing, similar to that of the stem 1, including a capillary passage 2a extending from the adjacent end of the chamber 4 and being open at the free end of the neck.

These pipettes are calibrated and may be graduated to indicate appropriate quantities of the blood and the diluent, such as 0.5 and 1 on the stem and 101 at the neck, in the case of pipettes for red corpuscle counts. These markings correspond to dilutions in the proportions of 101 to 0.5 and 101 to 1, respectively, as may be required with different diluting agents. In use, the pointed end of the pipette is applied to the blood source

or specimen and the blood permitted to rise in the capillary tube either to the marking 0.5 or to the marking 1, depending on the diluent. The latter is then sucked into the pipette until it fills the mixing chamber 4 and extends to the graduation marked 101.

The mixing chamber has loose within it a small mixing element or bead 6 which acts in the manner of a beater or stirring means, to facilitate and speed up the mixing of the blood and the diluent as the pipette is shaken or agitated, manually or otherwise.

It will be understood that in the usual manufacture of pipettes of this chambered type the manufacture proceeds from a capillary glass tube initially drawn in long lengths and cut as appropriate for the individual pipettes. A cut length of the tubing is heated at the section where the chamber is to be formed and while temporarily plugging the capillary at the appropriate point a generally globular chamber of the desired size is blown. Such chamber is completely closed except for the small ports at its opposite ends communicating with the central capillary passages of the stem and neck, such as 2 and 2a of Fig. 1.

The mixing element or bead 6 obviously must be larger than these capillary ports of the chamber, to retain the bead in the latter and to afford the desired mixing action.

30 A chief manufacturing problem, and that with which our invention is largely concerned, has been that of getting the mixing bead into the chamber. Heretofore the procedure for that purpose has involved heating and completely severing the pipette at the mixing chamber, near one or the other of its end portions, as for example at the point indicated by the broken line s—s, Fig. 7. This line of severance must be at a point along the chamber, spaced somewhat from one or the other end, such that the resulting aperture is of sufficient area to admit the bead. Following insertion of the bead the two completely severed sections of the pipette are heated and rejoined or fused together. This method has been slow and expensive, necessitating highly skilled workmanship to obtain satisfactory results.

Referring now more particularly to Figs. 2 to 5, as well as Fig. 1, it is noted first that the mixing chamber 4 as illustrated is of symmetrical and generally elliptical form, as contrasted for example with a usual previous formation substantially as represented in Fig. 7, wherein the portion of the chamber adjacent the body or stem of the pipette was of larger diameter than the rest of the chamber. The symmetrical for-

mation accorded the mixing chamber 4, as in Figs. 1 to 5, facilitates the bead-inserting process to be described, by making substantially any area upon the chamber wall available for the purpose, particularly a longitudinally central area.

After blowing the described mixing chamber 4, and noting now particularly Fig. 2, a lateral wall portion of the chamber is heated locally sufficiently to permit the flowing and drawing out of a relatively small section of the wall material, in a manner to form a protuberant conical nubbin or tip 7. This is readily accomplished by positioning the pipette substantially horizontally and operating at a then under portion of the chamber wall.

Such tip 7 is then severed as by cutting or breaking it off at its base, as for example in the plane indicated by the dotted line c—c of Fig. 2, at or close to the union of the tip with the surrounding unmodified portion of the chamber wall. The material of the tip preferably is so removed as to present a somewhat beveled or non-radial edge peripherally of the resulting opening 8, Fig. 3, thereby affording an annular seat 9 for the subsequent glass insert and closure means to be described.

The pipette is then turned to bring the aperture 8 into an up-facing position, as illustrated for example in Fig. 3. A mixing bead 6 is then inserted at and dropped through the opening 8 thus made available for the purpose. Such mixing bead 6, which is left entirely free within the chamber, may be of glass or other material, contrastingly colored or otherwise, and is of any appropriate shape and size such as not to decrease materially the liquid capacity of the chamber yet to assist in agitating and thoroughly commingling the different fluids contained.

The mixing element or bead 6 as shown by way of example consists of a short piece of a small pencil-like glass rod, thus resembling an ordinary glass bead, perforate or otherwise. Assuming Fig. 1 of the drawing to be substantially a full scale representation of one size and type of pipette, an appropriate mixing bead may be roughly $\frac{1}{8}$ in. long by $\frac{1}{16}$ in. in diameter, which dimensions may be considerably varied within the conditions above noted. The diameter of the bead-admitting aperture 8 for any particular pipette is made adequate for easy insertion of the given size and shape of bead.

After insertion of the mixing bead 6 the aperture 8 is reclosed and sealed in a manner to restore the chamber 4 to a fluid-tight condition and to confine the bead within it. Under the method of the invention, noting now Figs. 4 and 5, this is accomplished by means of a glass insert or plug 10, which, according to the size of the opening, may range from a globule to the small disk or button of glass as shown. Such closure member or insert 10 is placed in or on the receiving seat 9, its partly installed position being represented in Fig. 4. Heat is then applied locally around the juncture of the insert and the chamber wall so as to fuse together their constituent glass material.

The resultant closure or seal, as best seen in Figs. 5 and 6, conforms in general to the contour of the chamber wall, with the generally circular line of union scarcely discernible. The insert 10, however, desirably is of a thickness relative to the chamber wall as a whole and is so shaped at its outer surface as to be somewhat protuberant, presenting a shallow rounded projection or bump

adapted to serve as a stop against easy rolling of the pipette when it is placed on a flat surface. Since the described closure 10 thus incorporates a slightly greater mass of material than was removed to form the opening 8, the center of gravity of the chamber 4 is displaced laterally. Hence when the pipette is laid on a flat surface, such as a laboratory table, the slightly weighted region of the closure and stop formation 10, 11 automatically seeks a lowermost position, in contact with the flat supporting surface. The pipette having turned to such position, the protuberance or bump 11 is adequate to restrain further rolling under ordinary circumstances.

An additional advantage from the process of our invention may be had by contrastingly coloring the insert 10 in whole or part, as for example with the color blue, in contrast to the adjacent glass of the chamber wall and also in contrast to the color of the mixing bead. The latter generally is white in pipettes for white corpuscle counting and red in those intended for use in preparation for red corpuscle counts. By thus coloring or applying a color design to the plug 10 or the glass material thereof a readily visible marking is provided for identification purposes.

It will be understood that the glass of the pipette as a whole is clear and transparent save for the graduation marks and indicia such as previously mentioned and usually also a relatively narrow longitudinal background or reading strip 12, generally of a white or other enamel. Such strip affords a substantially opaque or semi-transparent zone against which to observe the content of the fine capillary passage 2, 2a with reference to the graduations and indicia.

While the bead-admitting aperture may be formed at any point circumferentially of the mixing chamber, it is preferably located at or within the opaque reading strip 12. In this manner the clear area of the chamber wall is retained in its original unmodified and unobscured condition.

Pipettes of the general character here concerned have heretofore usually been formed at their suction-applying or shorter end with a relatively small chamber-like enlargement such as indicated at M, Fig. 7, tapering outwardly and terminating at about the same diameter or somewhat smaller than the capillary sections of the pipette, but with an end opening of considerably larger diameter than that of the capillary passage. Such formation is believed to have been provided as a safety measure, when the technique called for the application of the pipette directly to the user's mouth, to suck the diluting liquid in at the opposite, pointed end. The chamber such as M was intended as a trap to receive any excess that might accidentally be drawn in, rather than to have it enter the user's mouth.

But under present practice, a length of rubber or other flexible tubing such as indicated at T, Fig. 1, is installed at the short or neck end of the pipette. The tubing may have a rigid mouth-piece P at its free end. The latter is inserted in the user's mouth, which is thus kept at some distance from the pipette itself, thus substantially eliminating the possibility of fluid from the pipette entering the person's mouth, or conversely the likelihood of any contaminant from the mouth being received by the content of the pipette.

In the improved pipette of our invention as here illustrated the installation of such tubing

is facilitated and the structure of the pipette itself materially simplified by a construction for the neck 5 substantially as illustrated in Fig. 1. As there seen the capillary passage 2a of the neck 5 is continued uniformly for substantially the full length of the latter. At or near the extreme outer end of the neck the outer cylindrical surface of the latter is provided with a protuberant annular formation, beading or rib 13 concentrically surrounding the end opening of the capillary passage 2a, which may there be slightly enlarged if desired. This rib 13 is relatively shallow and of rounded formation in cross-sectional contour, so that the end of the flexible tubing T, which is of a size to grip snugly about the pipette neck, is nevertheless easily forced onto the latter. The retaining rib 13 then serves to hold it securely against accidental displacement.

It will be understood that our invention, both as to method or product, is not limited to the exemplary steps or embodiment herein illustrated or described, and we set forth its scope in our following claim.

We claim:

In the manufacture of glass pipettes of the clinical type, that method which comprises the steps of forming a closed chamber of selected volume between opposed capillary tubular stems 5 having capillary ports communicating with the chamber, thereafter heating and forming to a projecting tip a single selected area of the mixing chamber wall spaced from the capillary ports, separating the tip at the outer surface of the chamber wall thereby to aperture it for inward passage of a mixing bead, freely passing such mixing bead from outside the chamber wholly through the wall aperture and so as to be loosely contained in the chamber, selecting a disk-like body of glass proportioned to seat peripherally at the aperture and of a composition visually contrasting with that of the chamber wall, and externally insetting and fusing such selected glass body at the aperture thereby reclosing it completely by glass wall-forming means and identifying the manufacture of the pipette.
